Primary Examiner — Raphael Barkai(74) *Attorney, Agent, or Firm* — Smith Risely Tempel Santos LLC; Gregory Scott Smith(57) **CLAIM**

The ornamental design for a temple for glasses, as shown and described.

DESCRIPTION

FIG. 1 is top plan view of a temple for glasses;

FIG. 2 is a bottom plan view of a temple for glasses;

FIG. 3 is a rear elevation view of a temple for glasses;

FIG. 4 is a front elevation view of a temple for glasses;

FIG. 5 is a right side perspective view of a temple for glasses, the left side view being a mirrored image;

FIG. 6 is a right side perspective view of a temple for glasses as viewed from the inside of the glasses, the left side view being a mirrored image;

FIG. 7 is a right side elevation view of a temple for glasses, the left side view being a mirrored image; and

FIG. 8 is right side elevation view of a temple for glasses as seen in view 8-8 of FIG. 1, the left side view being a mirrored image;

FIG. 9 is a right side elevation exploded view of the components of a temple for glasses, the left side view being a mirrored image; and,

FIG. 10 is a right side elevation exploded view showing a temple for glasses as viewed from the inside of the glasses, the left side view being a mirrored image.

The broken and grayed lines throughout the drawings form no part of the claim.
